BOOKKEEPING MECHANISM

Walter A. Brucker, Miami, Fla.

Application April 22, 1952, Serial No. 283,697

3 Claims. (Cl. 282—29)

1

This invention relates to bookkeeping devices, and more particularly to an improved bookkeeping mechanism which enables the accountant to accomplish in substantially a single operation the posting of data to an account card and simultaneously to a journal sheet.

A main object of the invention is to provide a novel and improved bookkeeping device enabling an accountant to accomplish in substantially a single operation the posting of data on an account card and simultaneously on the journal sheet, the device being arranged to allow the shifting of the journal sheet and account card to prevent damage to either the account card or journal sheet when working at the lower portions thereof, the improved device providing a saving in time in the entry of data, eliminating errors in transcribing, and being arranged to allow original entries to be made on account cards and identical entries to be made as carbon copies on the journal or summary sheet associated therewith.

A further object of the invention is to provide an improved bookkeeping device for speedily and accurately entering data on account cards and journal sheets, said device being simple in construction, being easy to operate, and being compact in size.

Further objects and advantages of the invention will become apparent from the following description and claims, and from the accompanying drawings, wherein:

Figure 1 is a fragmentary top plan view of an improved bookkeeping device constructed in accordance with the present invention.

Figure 2 is a top plan detail view of the sheet-holding clamping assembly employed in the bookkeeping device of Figure 1.

Figure 3 is a top plan detail view of the main bottom plate employed in the clamping assembly of Figure 2.

Figure 4 is a top plan detail view of the relatively wide outer clamp employed in the clamping assembly of Figure 2.

Figure 5 is a top plan detail view of the ground plate for the inner, relatively narrow clamp employed in the paper-holding assembly of Figure 2.

Figure 6 is a top plan view of the clamping arm of the inner clamp of the paper-holding assembly of Figure 2.

Figure 7 is an enlarged vertical cross sectional detail view taken on the line 7—7 of Figure 1.

Figure 8 is an enlarged vertical cross sectional detail view taken on the line 8—8 of Figure 1.

Figure 9 is an enlarged vertical cross sectional detail view taken on the line 9—9 of Figure 1.

2

Figure 10 is an enlarged vertical cross sectional detail view taken on the line 10—10 of Figure 1.

Figure 11 is an enlarged vertical cross sectional detail view taken on the line 11—11 of Figure 1.

Referring to the drawings, the bookkeeping device is designated generally at 11 and comprises a rectangular tablet 12 of rigid material which is reduced in thickness at one side margin thereof to define the upper marginal recess 13 and the lower marginal recess 14 (Figs. 7-11). Designated at 15 is an elongated flat plate member which is secured to the bottom surface of the tablet 12 along the reduced side margin thereof, as by the rivets 16 (Figs. 7, 11). The plate member 15 is formed with the spaced hinge loops 17, 18, 19 and 20 which are in alignment and which are disposed adjacent the marginal edge of the tablet 12 and which receive therein the hinge rod 21 (Figs. 7-11). Designated at 22 is a relatively wide, elongated, downwardly concave clamping plate which is formed with the hinge loops 23, 24 and 25 which are engaged on the hinge rod 21, as shown in Figure 2, the hinge loop 24 being received between the hinge loops 18 and 19, and the hinge loops 23 and 25 being located at the respective ends of the hinge rod. Designated at 26, 26 (Figs. 2, 7) are respective leaf springs which have substantially circular clamping portions 27 engaged around the hinge rod 21 between the respective hinge loops 17 and 23 and the hinge loops 25 and 20 and adjacent to hinge loops 18 and 19, as shown in Figure 2. The leaf springs 26 have lower arms 28 which are received in the recess 14, as shown in Figure 7, and have upper arms 29 which are received in apertured lugs 30 secured to the bottom surface of the clamping plate 22 adjacent its free edge. As shown in Figure 7, the free marginal portion of the clamping plate 22 is adapted to engage the top surface of the tablet 12, said free edge being bent to engage the top surface of tablet 12 substantially at right angles, as shown at 31. The leaf spring 26 bias the clamping plate 22 clockwise, as viewed in Figure 7, to provide clamping engagement of the edge 31 of the clamping plate against the tablet 12.

As shown in Figure 4, the clamping plate 22 is formed with the elongated notched portions 32, 32 for a purpose presently to be described.

The hinge lug 24 of clamping plate 22 has rigidly secured thereto the upwardly and outwardly extending finger tab 33 which is employed for manually rotating the clamping plate 22 upwardly when desired.

Designated at 34 is an elongated ground plate member which is formed with the spaced pairs of hinge loops 35, 35 and 36, 36, the hinge loops 35

being engaged inwardly adjacent the hinge loops 17, and the hinge loops 36 being engaged adjacent the spring 26, adjoining the hinge loop 19, as shown in Figure 2. The ground plate 34 is received in the upper marginal recess 13 of the tablet 12, as shown in Figure 8. The hinges 35, 35 and 36, 36, after engaging the hinge rod 21 extend under the lower marginal recess 14. Designated at 37 is a relatively narrow clamping plate which is formed with the hinge lugs 38 and 39, said hinge lugs 38 and 39 being engaged on the hinge rod 21 between the respective pairs of hinge loops 35, 35 and 36, 36, as shown in Figure 2. The clamping plate 37 is downwardly concave and disposed beneath the clamping plate 22, the clamping plate 37 being formed with a downwardly bent free marginal edge 40 which is adapted to engage the ground plate 34 substantially perpendicularly thereto, as shown in Figures 7 and 11. Designated at 41, 41 (Figs. 2 and 9) are respective clamping springs having U-shaped arms 42 engaging the top surface of the clamping plate 37 and having respective coiled portions 43, 43 surrounding the hinge rod 21, said coiled portions terminating in respective ends 44 bent sideways and engaged under the hinge loops 35, 35 and 36, 36, as shown in Figure 9, said springs being located adjacent the respective hinge lugs 38 and 39, as shown in Figure 2, and acting on the clamping plate 37 to bias said clamping plate downwardly into engagement with the ground plate 34. The clamping plate 37 is provided with the upwardly and outward inclined finger tabs 45, 45 which are employed to elevate the clamping plate 40 out of engagement with the ground plate 34 when desired, (Fig. 8).

It will be noted from Figure 2 that the hinge lugs 35, 35, 38 and 36, 36, 39 are located in the respective notched portions 32 of the outer clamping plate 22, whereby the inner clamping assembly comprising the ground plate 34, the clamping plate 37 and the springs 41 associated therewith may be moved longitudinally along the hinge rod 21. This may be accomplished by exerting a force on either of the tabs 45 in the direction of the axis of the hinge rod 21. This arrangement allows a sheet clamped by the inner clamping plate 37 to be moved parallel to the hinge rod 21 by merely exerting a slight downward pressure on the finger tab 33, to release the clamping force of the plate 22, and at the same time pushing one of the tabs 45 in the direction of the axis of the hinge rod 21.

In using the device, the journal sheet is inserted by depressing the tabs 45, 45, causing the free edge of the inner clamping plate 37 to be elevated against the spring arms 29, 29 and to exert an upward force on the outer clamping plate 22. The elevation of the outer clamping plate 22 on the inner clamping plate 37 allows the edge of the journal sheet to be inserted freely until it engages the inner end portion of the inner clamping plate 37. Also inserted in this manner is a sheet of carbon paper which overlies the left hand portion of the journal sheet and is arranged to underlie the account sheet to be next inserted in the device. The sheet or card is then inserted by depressing the tab 33 of the outer clamping plate 22, the account sheet then being moved beneath the clamp until its edge engages the vertical edge portion 48 of the inner clamping plate 37. The carbon paper and the left hand portion of the journal sheet are now covered by the account sheet or card. The account sheet or card is, of course, properly aligned with the journal

sheet so that the proper data may be entered simultaneously on the account sheet or card and the journal sheet, the data being transmitted to the journal sheet by the carbon paper disposed between the account sheet or card and journal sheet, as above described.

After completing the entry on the account card or sheet, said card or sheet may be removed by depressing the tab 33 to release the account sheet or card. The next account sheet or card may be inserted under the clamping plate 22 to perform the next bookkeeping entry.

In the course of the bookkeeping work the lower lines of the journal sheet will eventually be reached. Entries will be required simultaneously on the lower lines of the journal sheet and on the upper lines of account cards. Therefore, the account cards will protrude a considerable distance beyond the lower edge of the journal sheet and tablet, and in making entries, the account card may be creased or wrinkled because of this protruding position with respect to the lower edge of the tablet. In order to prevent such damage to an account card, the journal sheet may be shifted upwardly longitudinally along the hinge rod 21 in the manner above described, namely, by slightly depressing the tab 33 and simultaneously applying force on one or the other of the tabs 45 in the direction of the axis of the hinge rod 21, whereby the inner clamping device and the journal sheet and carbon paper carried therewith are moved along the hinge rod and relative to the notched portions 32 of the main clamping plate 22 until the inner clamping device engages its hinge 36 to the loop hinge 20 (Fig. 2). This moves the journal sheet upwardly to a more convenient position on the tablet wherein the account card may be positioned without protruding from the lower edge of said tablet, thus avoiding possible damage to the account card.

After the journal sheet has been filled with entries the journal sheet and carbon paper may be removed by depressing the finger tabs 45, 45, as above described, whereby the free edges of the outer clamping plate 22 and inner clamping plate 37 are simultaneously elevated. The inner clamping assembly comprising the clamping plate 37 and its ground plate 34 may then be returned to their original positions by pulling one or the other of the tabs 45 toward the lower hinge loop 17 of the outer clamping assembly (Figure 2).

While a specific embodiment of an improved bookkeeping device has been disclosed in the foregoing description, it will be understood that various modifications within the spirit of the invention may occur to those skilled in the art. Therefore, it is intended that no limitations be placed on the invention except as defined by the scope of the appended claims.

What is claimed is:

1. A bookkeeping device comprising a rigid rectangular tablet, a plate member secured to the bottom surface of said tablet and extending parallel to a side margin of the tablet, a plurality of hinge loops formed on said plate member adjacent the side marginal edge of the tablet, a hinge rod secured in said loops, a wide arcuate clamping plate pivoted on said rod and extending over said side margin, leaf springs operatively connected to the under face of said clamping plate biasing the clamping plate downwardly into engagement with the tablet to hold in its grip an account card, a narrow clamping plate pivoted to said rod and extending beneath the first-

named clamping plate, said second-named clamping plate being slidable on said rod, and spring means operatively connected to said second named clamping plate and biasing said second-named clamping plate into engagement with said tablet.

2. A bookkeeping device comprising a rigid rectangular tablet, a plate member secured to the bottom surface of said tablet and extending parallel to a side margin of the tablet, a plurality of hinge loops formed on said plate member adjacent the side marginal edge of the tablet, a hinge rod secured in said loops, a wide arcuate clamping plate pivoted on said rod and extending over said side margin, a plurality of leaf springs secured to said rod and the under side of said tablet, said springs biasing the clamping plate downwardly into engagement with the tablet, said clamping plate being formed with a plurality of longitudinal notches along said rod, a narrow clamping plate pivoted to said rod in said notches and extending beneath the first-named clamping plate, said second-named clamping plate being slidable on said rod, and spring means operatively connected to said second named clamping plate and biasing said second named plate into engagement with said tablet.

3. A bookkeeping device comprising a rigid rectangular tablet having a side margin of reduced thickness, a plate member secured to the bottom surface of said tablet and extending parallel to said side margin, a plurality of hinge loops formed on said plate member adjacent the side

marginal edge of the tablet, a hinge rod secured in said loops, a wide arcuate clamping plate pivoted on said rod and extending over said side margin, a plurality of leaf springs secured to said rod and the under side of the reduced margin of said tablet, said springs biasing the clamping plate downwardly into engagement with the tablet, said clamping plate being formed with two longitudinal notches along said rod, a narrow clamping plate pivoted to said rod in said notches and extending beneath the first-named clamping plate, a ground plate slidably engaged on said rod and slidably engaging the reduced side margin of the tablet, said second-named clamping plate overlying said ground plate and being slidable therewith relative to said rod, and spring means biasing the vertical free edge of said second-named clamping plate into engagement with said ground plate, for holding between the clamping plate and its ground plate a journal sheet and carbon paper.
